HYDRAULIC PRESS CONTROL SYSTEM

Frederick E. Munschauer, Jr., Buffalo, N. Y., assignor to Niagara Machine and Tool Works, Buffalo, N. Y.

Application October 7, 1949, Serial No. 120,041

1 Claim. (Cl. 121—38)

1

This invention relates to a hydraulic press or analogous machine and more particularly to novel arrangements for activating and controlling the operation of machines of this class.

In presses constructed according to the present invention, control means are provided whereby the effective pressure applied to the work by the hydraulic ram of the press is under ready and accurate control of the operator, so that, during the actual pressing operation, he may selectively apply any pressure between predetermined minimum and maximum limits.

Further, the control means is so arranged that the hydraulic activating means supplies fluid at relatively low pressure but in substantial volume when a working stroke of the press is initiated. In this initial phase of a working stroke the operator controls the rate or volume of liquid supplied to the hydraulic cylinder and thus readily and directly controls the speed at which the ram approaches the work. When a predetermined degree of resistance is encountered, as when the ram or a punch or the like held thereby meets the work or a die or other tool on the bed of the press, the high volume fluid supply means is automatically neutralized and pressure against the work at the aforesaid predetermined relatively low pressure continues until the operator further adjusts the control means to increase the applied pressure to any desired degree within the capacity of the apparatus.

In a preferred form of the apparatus of the present invention a single manually movable control device is provided which the operator moves to effect three distinct phases of press operation, namely, the approach of the ram to the work, the actual application of working pressure, and the return of the ram to its idle position, generally in a raised position above the bed of the press.

In the form of apparatus shown herein by way of example two fluid pressure generating pumps are utilized, both driven from a single power source. One of these pumps displaces liquid in relatively large volume at moderate pressure and the other is designed to develop high unit pressures, its volumetric capacity being relatively low.

In this way the driving motor of the press is utilized to the limit of its effectiveness in the various phases of press operation to the end that a driving motor of relatively low power output provides abundant energy for efficient operation. The sequence in which the two pumps become effective is entirely automatic, the operator of the press concerning himself solely with the functioning of the press ram in approaching the work, in

2

applying working pressure to the work, and in returning the ram to idle position.

Numerous advantages inherent in apparatus arranged according to the principles of the present invention will occur to those skilled in the art to which it pertains from a study of the following specification and the accompanying drawings. However, it is to be understood that the embodiment thus described and illustrated in detail is by way of example only and that numerous mechanical and hydraulic variations may be made without departing from the underlying principles of the invention, the spirit and scope of which is limited only as defined in the appended claims.

15 15 In the drawings:

Fig. 1 is a general side elevational view of one form of press having operating and control means according to the principles of the present invention and with portions thereof broken away for added illustration;

20 Fig. 2 is a detail view of the manual control lever for the machine of Fig. 1, viewed from the front;

25 Fig. 3 is a schematic layout of the hydraulic circuits and units which power and control the operation of the movable ram of the press;

30 Fig. 4 is an enlarged and more detailed view, partly in cross-section of a four-way valve and remote pressure relief valve which ultimately control the operation of the press ram, these units being shown in their operative hydraulic circuit connected relation in Fig. 3;

35 Fig. 5 is a detailed cross-sectional view of a sequence valve which performs the main pressure regulating function in the higher pressure range;

Fig. 6 is a detailed cross-sectional view of an unloading valve for neutralizing the large-volume, low-pressure pump in the higher pressure range; and

40 Fig. 7 is a detailed cross-sectional view of a foot valve which prevents the ram from settling when it is at rest in its upper idle position.

Throughout the several figures of the drawing like characters of reference denote like parts, and reference will first be had to the general side elevation view, Fig. 1, which shows a press frame 10 having a work or die receiving bed 11, and a vertically reciprocable ram 12. A rock shaft 13 extends fore and aft of the press frame and has a manually operable lever 14 at its front end and an oppositely directed rock arm 15 at its rear end. A lever or rocker arm 16 is pivoted to the press frame as shown in the upper right-hand portion of Fig. 1, and a vertical link 17 connects one arm of lever 16 with the outer end

of rock arm 15. A generally vertically disposed link 18 extends downwardly from the other end of lever 16, and the manner in which vertical movement of link 18 effects control of the movements and effective pressures of ram 12 will presently appear.

Reference will now be had to the schematic layout, Fig. 3, which shows the various hydraulic circuits and control devices which cooperate to provide the novel control arrangement for hydraulic presses which forms the subject of the present application.

Referring to Fig. 3, the numeral 20 designates a hydraulic press cylinder, and a piston element 21 therein has a depending piston rod 22 which connects with the usual hydraulic press ram, such as is indicated at 12 in Fig. 1.

A common operating motor 24 has opposed drive shafts 25 and 26 which are flexibly connected to a pair of hydraulic pumps 27 and 28. Pump 27 is of large volumetric capacity, developing relatively low pressures, while pump 28 has a relatively small volumetric capacity and develops very high pressures. In one practical application of the principles of the present invention, merely by way of example, pump 28 has a maximum output pressure of 2,000 pounds per square inch.

It is common in hydraulic press construction to mount the several control valves and the pump or pumps in a tank which contains the hydraulic medium supply, so that all of these devices, excepting the electrical motor, are continuously submerged. This same procedure is contemplated in the case of the present invention, but for convenience of understanding the various control devices are shown in Fig. 3 as having tank, reservoir or drain connections. In the case of pumps 27 and 28 their intake ports are shown to have theoretical tank connections at 31 and 32, respectively.

The various control units will now be enumerated generally and their construction and co-operation with each other will then be described in greater detail. Referring to Fig. 3, the numeral 34 designates an unloading valve for large pump 27, and the numeral 35 designates a check valve which permits free fluid flow away from the output side of pump 27 but prevents retrograde flow. The numeral 36 designates a conventional, manually-operated four-way valve for controlling fluid flow to cylinder 20 above and below piston 21.

The numeral 37 designates a pressure regulating valve which is disposed generally in the output line from the small high pressure pump 28, and operation of the regulating valve is controlled in the first instance by a remote, manually-operated relief valve 38.

Fluid pressure flow from pump 27 to four-way valve 36 is by means of a conduit 40 from pump 27 to unloading valve 34, a conduit 41 from the latter to check valve 35 and a conduit 42 from the check valve to an intake port 43 of four-way valve 36, the latter being shown in detail in Fig. 4.

Output pressure from small pump 28 goes to pressure regulating valve 36 by way of a conduit 45, and thence, by way of a conduit 46, to a connection with conduit 42, whereby they jointly lead to the supply port 43 of four-way valve 36.

In Fig. 3 the numeral 48 designates a foot valve, which is merely a special check valve which keeps the ram of the press from settling due to the leakage past four-way valve 36 when

the latter is in neutral position. Four-way valve 36 has one of its output passages 50 connected to the top of cylinder 20 by means of a conduit 51, and the other output passage 52 of four-way valve 36 connects to the foot valve 48 by means of a conduit 53 and thence to the bottom of cylinder 20 by means of a conduit 54.

When four-way valve 36 is in the position illustrated in Fig. 4 valve heads 55 and 56 block both outlet ports 50 and 52 and the valve is in neutral position. A conduit 58 drains back to the tank or reservoir and connects with a pair of discharge ports 60 and 61. If valve heads 55 and 56 are jointly lowered, supply passage 42 is connected with the top of cylinder 20 by means of port 50 and conduit 51 and the bottom of cylinder 20 is permitted to drain by way of the port 52 of four-way valve 56 and drain passage 61 leading to the tank connection 58. Obviously, if valve heads 55 and 56 are jointly raised from their illustrated neutral position the pressure and drain connections to cylinder 20 are reversed.

Referring at this point to foot valve 48, it will be noted that this valve contains two parallel passages designated 65 and 66. Passage 65 is provided with a check valve 67 which is biased by means of an adjustable compression coil spring 68. Accordingly, fluid flow from the bottom of the cylinder through conduits 54 and 53 can only be achieved by unseating check valve 66 which requires an adjustable degree of pressure sufficient to prevent the ram from settling of its own weight, but not so great as to prevent unseating of check valve 66 when positive pressure is applied to the top of piston 21.

When valve heads 55 and 56 are moved upwardly from their illustrated position in Fig. 4, the bottom portion of cylinder 20 is connected with the pressure supply conduit 42, and the top of cylinder 20 is connected with drain conduit 53. In this phase of operation, again referring to foot valve 48, a check valve 70, which prevents flow through passage 66 from conduit 54 to 53, permits free passage of fluid through passage 66 from conduit 53 to conduit 54. It will thus be noted that foot valve 48 provides substantially no resistance to fluid flow into the bottom of cylinder 20 but imposes a controlled degree of resistance to fluid flow therefrom.

Reference will now be had to the pressure regulating valve 37 and remote relief valve 38, which are shown in greater detail in Figs. 5 and 4, respectively. Remote relief valve 38 has a chamber 73 which connects a fluid inlet port 74 and a passage 75 which leads freely to the fluid tank or reservoir. Inlet port 74 is normally closed from chamber 73 by a valve 76 which is urged to closed position by operation of a compression coil spring 77, whose initial pressure, as illustrated in full lines in Fig. 4, is sufficient to cause the valve to remain closed until pressure in inlet port 74 reaches approximately 200 pounds per square inch, by way of example. The bottom end of spring 77 seats against a disc 78, which is fixed to an axially slideable bar 79. Manual pressure may be exerted temporarily against bar 79 to further compress spring 77 and thus temporarily increase in a selectively variable manner the unit pressure required in port 74 to unseat valve 76 and thus relieve pressure in inlet port 74 through chamber 73 and drain passage 75.

Referring to pressure regulating valve 37, the main fluid passage therethrough is designated 83 and connects at opposite ends with conduits 45 and 46, which lead from the output side of small

pump 28 to the pressure supply passage 42. Regulating valve 37 further has a relief or drain passage 81, which is normally closed by an axially movable valve 82.

The body of regulating valve 37 has a bore 84 extending transversely from the main fluid passage 80 and valve 82 has a cylindrical enlargement 85 which is axially slideable in bore 84. A very light compression coil spring 86 acts against cylindrical enlargement 85 to bias valve 82 slightly to a downward closed position as illustrated in Fig. 4.

A passage 87 leads from the upper end of bore 84 and connects with inlet port 74 of remote relief valve 38 as by means of a conduit 88. A passage 90 leads from passage 87 to a chamber 91 which houses a pressure relief valve 92 and a compression coil spring 93 which acts against valve 92. The bias of spring 93 may be varied by means of an adjusting screw 94, the pressure of spring 93 on valve 92 being proportional to and determining the maximum pressure which may be transmitted to cylinder 20 by operation of the small capacity, high pressure pump 28 when the ram of the press is meeting sufficient resistance to develop maximum pressure. A conduit 96 leading from chamber 93 provides a drain passage for liquid which passes valve 92 when the latter is unseated to relieve pressure. A relatively small bore 98 extends through cylindrical enlargement 85 of valve 82.

The construction of unloading valve 34 will now be described, reference being had particularly to Fig. 6. This valve is provided with a bore 100 in which a valve element 101 is axially slideable, valve 101 having a pair of valve heads 102 and 103. Liquid from the output conduit 40 of large pump 27 is delivered to bore 100 between the valve heads 102 and 103 and normally passes from bore 100 by way of conduit 41 which leads to check valve 35. The lower end of valve 101 comprises a relatively small diameter piston 104 which is axially movable in a chamber 105 which connects freely with the main fluid passage 80 of regulating valve 37 as by means of conduit 106, see Figs. 3, 5, and 6.

The fluid pressure in chamber 105, which is normally the same as that obtaining in passage 80 of regulating valve 37, is counteracted, up to predetermined limits, by a compression coil spring 110 which acts against the opposite end of valve 101 and whose pressure is adjustable by means of an adjusting screw 111.

Four-way valve 36 and the remote relief valve 38 are both operated by means of a single control arm 115 in a manner which is best illustrated in Fig. 4. The left-hand end of arm 115 is pivotally connected to the lower end of link 18 which has previously been described. The manner in which link 18 is moved up and down by manipulation of the remotely located hand lever 14 and the lever and linkage connection therebetween has also been described previously herein.

Referring to Fig. 4, a lever 116 is pivoted to a fixed part of the machine as at 117 and has pivotal connection with the outer end of rod 79 of remote relief valve 38, as at 118. An extension spring 120 connects at one end with lever 116, and its opposite end is connected to a fixed part of the machine as at 121. The outer end of lever 116 is pivotally connected to control arm 115, and the latter has an intermediate pivotal connection 124 with the outer end of valve rod 125 which carries the valve heads 55 and 56 of four-way valve 36.

In the full-line position illustrated in Fig. 4, rod 79 of remote relief valve 38 is fully withdrawn and is held in such position by extension spring 120, and valve rod 125 of four-way valve 36 is in the neutral position illustrated. If lever 115 be moved upwardly to the position indicated at A in Fig. 4, the rod 125 of four-way valve 36 will be moved to connect the lower end of cylinder 20 with pressure supply passage 42, and piston 21 will move upwardly. Since the resistance to this movement is relatively low, the movement will be accomplished rapidly, mainly by fluid from large capacity pump 27, the pressures generated being not high enough to cause unloading of pump 27 by operation of unloading valve 34.

If lever 115 be moved downwardly to the position illustrated at B in Fig. 4, a reverse operation takes place until the ram of the press encounters material resistance, as by meeting the work in the press. At this point the pressure in conduits 40, 41, and 42 rises through continued operation of both pumps 27 and 28 until the pressure in chamber 105 of the unloading valve is sufficient to move the valve heads 102 and 103 upwardly to a point where the latter blocks further communication between conduits 40 and 41, and valve 102 also moves upwardly to uncover a passage 128 of unloading valve 34, which is a drain passage. The position of valve heads 102 and 103 in Fig. 6 is an intermediate position. The setting of spring 110 may be assumed to be such as to unload pump 27 by operation of valve 34 when the pressure in conduit 42 reaches 175 pounds per square inch. This pressure is assumed here merely for illustrative reasons and for comparison with pressures developed in the remote relief valve 38.

Assuming that lever 115 is not moved downwardly beyond the position indicated at B in Fig. 4, the rod or stem 79 of remote relief valve 38 will not be operated, and that valve will be in the condition illustrated in Fig. 4. At this point, valve rod 125 of four-way valve 36 is fully withdrawn, but the force of extension spring 120 is still operating to maintain rod 79 in its withdrawn position.

Immediately upon unloading of large pump 27 and because of the continued resistance to movement of piston 21 in cylinder 20, pressure in conduit 42 will tend to continue to rise by continued operation of high pressure low capacity pump 28. Such a tendency to increase pressure in passage 80 causes enlargement 85 to move upwardly, since spring 86 is merely a light biasing spring and orifice 98 through enlargement 85 is too small to permit rapid equalization of pressure above and below enlargement 85. This opens valve 82 in an amount and for a time sufficient to regulate the pressure in passage 80.

As the increased pressure tendency in passage 80 continues, fluid through orifice 98 gradually increases the pressure above enlargement 85 and this, through the equalizing action of enlargement 85 and valve 82 produces a corresponding increase in pressure in passage 80. This continues until the pressure in conduit 88, and consequently in the intake port 74 of remote relief valve 38, reaches the initial pressure setting of spring 77 against valve 76, whereupon the latter unseats and liquid drains through chamber 73 and passage 75. This unbalances the pressure at the top and bottom of enlargement 85 and unseats valve 82 to establish pressure in passage 80 equal to that established in conduit 88 by operation of spring 77 and valve 76. Valve 76

thus serves as a pressure limiting valve for conduit 88 and the space above enlargement 85, and the pressure in main passage 80 of the regulating valve 37 is thus fixed at a maximum determined by the initial tension setting of spring 77, for instance 200 pounds per square inch, as long as lever 115 does not move downwardly beyond the position indicated at B in Fig. 4.

In movements of lever 115 from the neutral position to the positions indicated at A and B in Fig. 4, the speed of movement of piston 21 is proportionate to the degree of displacement of lever 115 from the neutral position since such degree of displacement is reflected in the degree to which ports 50 and 52 of the four-way valve 36 are exposed. This provides a very natural and convenient control of ram movement on the part of the operator during downward approaching movement of the ram and also during upward return movement.

As lever 115 is moved beyond the position indicated at B in Fig. 4, toward the limit position indicated at C, rod 125 of the four-way valve 36 has been fully withdrawn, and thus further movement of lever 115 moves lever 116 upwardly against the resistance of spring 120, pivot 124 now serving as a fixed fulcrum for lever 115, and rod or stem 79 of remote relief valve 38 is moved upwardly as viewed in Fig. 4. This causes collar 78 to apply greater pressure to spring 77 and thereby to valve 76.

This increased pressure is proportionate to the degree of displacement of lever 115 from position B toward position C in Fig. 4, and permits the pressure in conduit 87 and above enlargement 85 to increase by fluid flow upwardly through orifice 98. It will be remembered that the pressure potential of small pump 28 is such that it constantly tends to increase the pressure in passage 80 up to the maximum output pressure of the pump. In this manner the pressure in passage 80 is manually controlled by movement of lever 115 between positions B and C, and pressure thus applied to the top of cylinder 20 is limited only by the full capacity of pump 28 or the relieving operation of valve 92, which occurs only at a maximum press-capacity setting, for instance 2,000 pounds per square inch.

Here again the control of the degree of pressure by the operator in the range from position B to position C is extremely natural and simple for the operator and he may guide his movements of lever 14 by reference to a pressure gauge which may be located conveniently and which is indicated schematically at 130 in Fig. 3. Safety is promoted by the fact that working pressures can only be developed in the range from B to C and if the operator releases the manual lever 14 the control arm 115 will automatically be moved back to the lower pressure position B by operation of spring 120.

A further safety arrangement for insuring neutralization of the controls when the press ram reaches predetermined upper and lower limit positions will now be described, and in that connection reference is had to Fig. 1. Rock shaft 13 has fixed thereto an arm 131 which extends to the left from rock shaft 13, as viewed from the front

of the press, and pivotally engages at its outer end a vertically extending rod 132. The upper end of rod 132 extends slidably through a guide 133, which may be a fixed part of the press frame. Rod 132 has adjustably fixed thereto an upper stop collar and a lower stop collar 135. A bracket 138 is fixed to ram 12 and has a rearwardly extending arm portion 139 which extends through a slot 140 in the press frame and alongside of rod 132.

If the operator should keep the control lever 14 in a raising position for too long a time, the bracket 138 will move upwardly with ram 12 until it strikes collar 124, whereupon it will raise rod 132, move rock shaft 13 in a clockwise direction as viewed from the front of the press, and move the control linkage to neutral position. Conversely, if the operator tends to permit the ram to move downwardly beyond its safe limit of operation, bracket 138 strikes collar 135, lowering rod 132, thus again moving the control linkage to neutral position.

What is claimed is:

In a hydraulic press or similar machine comprising a cylinder and a ram piston reciprocable therein, a source of hydraulic pressure and conduit means for communicating said pressure to the cylinder to act against said ram piston, reversing valve means having a neutral position for blocking said conduit means and two operative limit positions for selectively applying the pressure from said source to either end of the cylinder, a relief valve acting upon the conduit means and normally establishing a predetermined minimum pressure therein, said relief valve having movable means for variably increasing said predetermined minimum pressure setting, a manual control lever having a yieldably movable fulcrum, means connecting said reversing valve means with said control lever whereby movement of the lever in opposite directions on said yieldable fulcrum moves the reversing valve means to either of its limit positions, and means engageable between said yieldable fulcrum and said relief valve movable means whereby movement of said lever beyond the point where the reversing valve connecting means has reached its limit position in one direction moves said yieldable fulcrum to act upon said relief valve movable means to communicate to said cylinder selectively variable pressures in excess of said predetermined minimum.
